HANGER FOR BLUEPRINTS OR THE LIKE

Denzil B. Cain, Parkersburg, W. Va.

Application October 7, 1939, Serial No. 298,509

4 Claims. (Cl. 24—154)

This invention relates to a hanger for blueprints or the like, and it is an object of the invention to provide a device of this kind which can be readily applied to the sheets whereby such sheets can be filed without folding or rolling and in a manner to obtain economy in the space required.

Another object of the invention is to provide a device of this kind which is provided with means whereby the same may be effectively locked to a supporting bar or can be readily removed when desired.

It is also an object of the invention to provide a device of this kind constructed in a manner to provide for tabulation and thus doing away with the use of separate tabs.

The invention consists in the details of construction and in the combination and arrangement of the several parts of my improved hanger for blueprints or the like whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary view partly in section and partly in elevation illustrating hangers constructed in accordance with an embodiment of my invention in working position;

Figure 2 is an enlarged rear elevational view of a hanger as herein disclosed unapplied;

Figure 3 is an enlarged sectional view taken substantially on the line 3—3 of Figure 1, the hanger bar being in fragment and in elevation.

My improved hanger as herein disclosed comprises a rectangular sheet body 1 of a metal or fibre possessing the requisite strength and rigidity. This sheet body 1 is elongated and relatively wide and preferably substantially rectangular in form.

One end portion of the sheet body 1 is provided with an upwardly disposed extension or plate 2. This extension or plate 2 is relatively wide and has its periphery arcuate for an extent in excess of a semi-circle. A portion of the sheet body 1 to one side of the extension or plate 2 provides a surface of sufficient area to allow the placement thereon of desired tabulations as indicated at 3. Overlying the rear face of the extension or plate

2 is a second plate 4 of a contour substantially the same as the extension or plate 2.

The plates 2 and 4 at the axial center of their arcuate peripheries are tied or connected by a grommet 5. This grommet 5 provides a mounting for a disk 6 interposed between the plates 2 and 4 and which has serrated portions 7 in diametrically opposed relation which extend beyond the peripheries of the plates 2 and 4 to provide means whereby the disk 6 may be readily rotated.

The upper portions of the plates 2 and 4 are provided with the transversely aligned slots 8 open at their outer ends and the upper portions of which are adapted to be intersected by the hook 9 resulting from the bayonet slot 10 cut in the peripheral portion of the disk 6.

The plate 4 is provided with an extension or plate 11 which extends transversely across the end portion of the sheet body 1 immediately below the extension or plate 2, and this plate 11 at substantially its junction with the plate 4 is secured to the sheet body 1 by a staple 12 or the like whereby the plates 4 and 11 are maintained in desired position and against rotation about the grommet 5. The lower or free end portion of the plate 11 at substantially its transverse center has disposed therethrough a grommet 14, the opening of which aligns with the opening of a grommet 15 disposed thru the adjacent lower end portion of the sheet body 1. As is clearly illustrated in the accompanying drawing, the plates 4 and 3x each comprise a single elongated wide sheet.

The plate 11 below its fastening 12 is entirely free of the sheet body 1 whereby a marginal portion of a blueprint or kindred sheet may be readily inserted between the plate 11 and the adjacent end portion of the sheet body 1 after which a suitable securing member 16, which may be as desired, is inserted through the grommets 14 and 15 and the portion of the sheet S inserted between the sheet body 1 and the plate 11.

Two or more of my improved hangers are preferably used in connection with a blueprint or kindred sheet S and the disk 6 of each of the hangers is rotated to open the slots 10 whereupon the hanger is engaged from below the bar 18 of a filing cabinet or the like, said bar being received within the slots 10. The disk 6 is then rotated to cause the hook 9 to extend across the top of the bar 18 and to close the upper open portions of the slots 8.

By the use of my improved hanger it is believed 55

to be apparent that a blueprint or kindred sheet 5
may be effectively supported or filed away without
folding or rolling and in a manner whereby
a print or sheet can be readily removed without
disturbing other prints or sheets. It is also believed
10 to be apparent that with the use of my improved hanger a print or sheet is suspended in a manner whereby the liability of the hangers becoming loose from the bars is substantially
15 eliminated.

From the foregoing description it is thought
to be obvious that a hanger for blueprints or the
like constructed in accordance with my invention
15 is particularly well adapted for use by reason
of the convenience and facility with which it
may be assembled and operated, and it will also
be obvious that my invention is susceptible of
20 some change and modification without departing
from the principles and spirit thereof and for this
25 reason I do not wish to be understood as limiting
myself to the precise arrangement and formation
of the several parts herein shown in carrying out
my invention in practice except as hereinafter
claimed.

25 I claim:

1. A hanger of the class described having a
long and wide sheet body provided at one end
portion with an upstanding plate, a second plate
30 overlying the first plate, said second plate being
continued by a third plate extending across the
adjacent end portion of the sheet body, the upper
portions of the first two plates being provided
35 with registering open slots, a member disposed
through and connecting the first two plates, a
disk arranged between said first two plates and
rotatably supported upon the connecting member,
the peripheral portion of the disk being provided
40 with a hook to extend across and close the
upper end portions of the slots in the first two
plates, and means for securing the upper portion
of the third plate to the sheet body whereby the
major portion of said third plate is free from
45 the sheet body to provide for insertion of the
marginal portion of a sheet between the sheet
body and the third plate.

2. A hanger of the class described having a
long and wide sheet body provided at one end
portion with an upstanding plate, a second plate
50 overlying the first plate, said second plate being
continued by a third plate extending across the
adjacent end portion of the sheet body, the upper
portions of the first two plates being provided
55 with registering open slots, a member disposed
through and connecting the first two plates, a
disk arranged between said first two plates and
rotatably supported upon the connect-

ing member, the peripheral portion of the disk
being provided with a hook to extend across and
close the upper end portions of the slots in the
first two plates, and means for securing the upper
portion of the third plate to the sheet body 5
whereby the major portion of said third plate is
free from the sheet body to provide for insertion
of the marginal portion of a sheet between the
sheet body and the third plate, the disk having
a portion extending beyond the first two plates 10
to provide means for rotating the disk.

3. A hanger of the class described having a
long and wide sheet body provided at one end
portion with an upstanding plate, a second plate
overlying the first plate, said second plate being
continued by a third plate extending across the
15 adjacent end portion of the sheet body, the upper
portions of the first two plates being provided
with registering open slots, a member disposed
through and connecting the first two plates, a
disk arranged between said first two plates and
20 rotatably supported upon the connecting member,
the peripheral portion of the disk being provided
with a hook to extend across and close the
upper end portions of the slots in the first two
plates, and means for securing the upper portion
25 of the third plate to the sheet body whereby the
major portion of said third plate is free from the
sheet body to provide for insertion of the marginal
portion of a sheet between the sheet body and
the third plate, the lower portion of the third
30 plate and the adjacent portion of the sheet body
having substantially registering openings.

4. A hanger of the class described having a
long and wide sheet body provided at one end
portion with an upstanding plate, a second plate
overlying the first plate, said second plate being
continued by a third plate extending across the
35 adjacent end portion of the sheet body, the upper
portions of the first two plates being provided
with registering open slots, a member disposed
through and connecting the first two plates, a
disk arranged between said first two plates and
40 rotatably supported upon the connecting member,
the peripheral portion of the disk being provided
with a hook to extend across and close the
upper end portions of the slots in the first two
plates, and means for securing the upper portion
45 of the third plate to the sheet body whereby the
major portion of said third plate is free from the
sheet body to provide for insertion of the marginal
portion of a sheet between the sheet body and
the third plate, the first and third plates comprising
50 a single elongated and wide sheet.

DENZIL B. CAIN.
